9 Claims. (Cl. 15—41)

1

This invention relates to improvements in carpet sweepers. It relates particularly to improvements in the suspension of carpet sweepers and to the mechanical relationship between the wheels and the brush. Further, the invention relates to various improvements in stabilization and control of carpet sweepers made possible by the improvements in brush and wheel operations.

Conventional carpet sweepers comprise a casing supported at either end by a pair of laterally spaced wheels, and operable by an extended handle connected to the casing by a U-shaped bail. A brush is rotatably mounted on the longitudinal axis of the casing, the opposite ends of the brush axle extending between the opposite pairs of wheels and in frictional engagement therewith. Motion of the sweeper over a carpet causes the wheels to rotate thereby imparting rotary motion to the brush. A pair of dust pans disposed in the housing on either side of the brush, collect the sweepings as the brush rotates. To permit withdrawal and insertion of the brush, the wheels are suspended in laterally movable manner so that they may be spread. A spring urges the wheels against the brush axle and tends to prevent spreading of the wheels when the sweeper is in operation.

In early sweepers the brush was journaled to the casing and was not free to move laterally during operation. As a result of the resilient mounting, the trailing wheels tended to spread so as to impair the frictional engagement with the brush axle. In an earlier Patent No. 2,166,977, I disclosed means whereby the brush could shift laterally along with the wheels so as to provide positive drive by all of the wheels. The present invention provides improvements in this lateral brush shifting means.

Partly in consequence of the so-called floating wheel suspension which results in a shift of the support points, the distribution of downward pressure on the sweeper case varies with the direction of travel of the sweeper. Thus the pressure on the leading wheels on the floor and against the brush pulley is generally greater than the pressure on the trailing wheels. Stabilizing means are provided in the sweeper of the present invention which equalize this downward thrust regardless of the direction of travel.

To increase the utility of carpet sweepers of the type described, means are generally provided to vary the relative elevation of the brush with respect to the wheels. For thick rugs, for example, it is desirable to elevate the brush with respect to the wheels and comparatively with re-

2

spect to the floor so as to reduce the resistance to travel. The converse is true when sweeping thin rugs. In my Patent No. 2,239,276, I describe a brush adjusting mechanism whereby the brush may be raised and lowered. The mechanism there described is particularly adapted to use in the sweeper described in my previously mentioned patent wherein the brush is free to move laterally, so that the axles of the wheels and the brush shift as a unit upon changing the direction of sweeping.

In the present invention, I provide an improved brush shifting means and I also provide improved means for adjusting the relative positions of the wheels and the brush. Although the improved adjusting means are adapted to cooperate with the improved shifting means, they are also applicable to other forms of carpet sweepers. The adjusting means as hereafter more fully described, may take several forms. One such form involves positive vertical displacement of the brush by means of a cam on the bail and a counteracting spring. Another means, of which several embodiments are illustrated, involves the positive displacement of the wheels by means of a cam on the bail and a counteracting spring. A third adjusting means utilizes the tendency of the brush to seek its own level, making provision at the same time for the improved lateral displacement of the brush as herein set forth.

Other improved features of the carpet sweeper of the invention will become apparent from the following detailed description.

In one embodiment, my improved carpet sweeper comprises a casing having floor wheels arranged in pairs at opposite ends thereof and rotatable from separate hangers mounted to the ends of the casing in laterally pivotal and vertically displaceable relationship. A rotary brush extends the length of the casing and is provided with a pair of pulleys, one at each end thereof, each pulley being in frictional engagement with the corresponding pair of ground wheels. An elongated handle is affixed to the casing by means of a bail having two legs pivotally affixed at opposite ends of the casing. An elongated spring, hereinafter referred to as the "stabilizer spring," is mounted on each end of the chassis. The stabilizer spring is secured to the front and rear of the end member and bows upwardly in the center. The bail depresses the central portion of each of the springs adjacent the point of attachment of the bail to the casing thereby distributing the downward thrust equally to the front and rear of the casing.

A cover plate is affixed to each end of the casing and is spaced therefrom to form a housing for the wheels and brush pulleys. Each of the cover plates carries a pivotally mounted tongue to which the opposite ends of the rotary brush are journalled. The pivoting of the opposed tongues permits lateral motion of the brush in unison with the lateral displacement of the ground wheels. The tongues may be sprung away from the casing to permit insertion and retraction of the rotary brush.

In one embodiment of the invention each tongue is provided with restricted vertical freedom whereby the elevation of the brush with respect to the wheels may be adjusted by means hereinafter described. In another embodiment of the invention means are provided for adjusting the elevation of the wheels, and in still another embodiment means are provided for simultaneously adjusting relative positions of both the brush and the wheels. The adjustment in this latter instant is in opposite directions so that the absolute displacement of either the wheels or the brush for a given relative displacement is one-half that required if all the adjustment is accomplished through displacement of one or the other.

The foregoing and other features of the invention will be more clearly understood from the following detailed description thereof taken in relation to the accompanying drawing in which:

Fig. 1 is a side elevation of one sweeper according to the invention;

Fig. 2 is a sectional elevation taken on the line 2-2 of Fig. 1;

Fig. 3 is a side elevation of the central portion of one of the end plates of the sweeper of Fig. 1 with certain features shown in phantom so as to permit illustration of other features;

Fig. 4 is an end elevation of the sweeper of Fig. 1 with the cover plate removed to show the wheel mounting, the bale mounting and the stabilizer spring;

Fig. 5 is a partial elevation of a simplified means of brush mounting taken on the line 5-5 of Fig. 6;

Fig. 6 is a partial sectional elevation of this simplified mounting means;

Fig. 7 is a sectional elevation similar to Fig. 2 showing an alternative form of the invention;

Fig. 8 is an elevation taken on the line 8-8 of Fig. 7;

Fig. 9 is a detailed view of one end of the bail member showing the means of engagement thereof with the stabilizer spring;

Fig. 10 is an end elevation of another embodiment of the invention with the cover plate removed to show the wheel mounting and means for raising and lowering the wheel;

Fig. 11 is an elevation looking toward the inside face of a cover plate used in an alternative embodiment of the invention showing means for raising and lowering both the brush and the wheel;

Fig. 12 is an end elevation of another embodiment of the invention with the cover plate removed to show an alternative form of wheel mounting; and

Fig. 12A is a section taken on the line 12A-12A of Fig. 12.

The carpet sweeper of my invention comprises a casing C which includes an end plate 10, an identical opposite end plate (not shown), and a cover plate 12 spaced from the end plate 10 and a second cover plate (not shown) spaced from the opposite end plate (not shown). The casing 75

is supported on two pairs of floor wheels, the wheels 14, 15, situated between the end 10 and a cover plate 12 being shown in the drawing. Throughout the description of the invention, it is to be understood that the arrangement of wheels and associated mechanisms at one end of the sweeper is identical to that at the opposite end and description of one will suffice for both.

As best shown in Fig. 4, which is an end view of the sweeper of Fig. 1, wherein the cover plate 12 has been removed and a portion of the wheels have been cut away, the wheels 14, 15 are rotatably mounted to the end plate by means of hangers 16, 17 respectively. The hangers 16 and 17 are pivotally mounted to the pintles 18, 19 respectively affixed to the end 10. The hanger 16 is slotted at 20 to permit vertical as well as pivotable motion of the hanger. The hanger 17 is similarly constructed. The wheels are journalled to the lower portions of the respective hangers by means of axles 22, 23 respectively. A spring 25 anchored to the end 10 at 26 and 27 and attached at opposite ends to the axles 22, 23 of the two wheels urges the wheels inwardly against a pulley 30 formed on one end of an axle 31 of a rotary brush 32. Rotation of the wheels 14 and 15 causes rotation of the brush 32 by frictional engagement of the wheels with the pulley 30. Pivotal mounting of the wheels is necessary so that they may be spread during insertion of the brush.

As best shown in Fig. 2, the axle 31 of the brush 32 is mounted to a tongue 34. The tongue 34 is pivotally mounted to the cover plate 12 on a pintle 36 rigidly affixed to the tongue and rotatably riveted to the cover plate 12. The cover plate 12 is inset at 38 and slotted at 39 in the off-set portion separating the inset 38 from the rest of the cover plate. The tongue 34, which is pivotally mounted at its upper end against the inner face of the plate 12 projects through the slot 39 and lies against the outer face of the plate 12 below the slot 39 and in the inset portion 38. To permit insertion and withdrawal of the brush 32 the tongue 34 may be sprung away from the plate 12. A rubber bumper 40 circumscribes the casing and cover plate, and is sufficiently elastic to permit flexing of the tongues.

The axle 31 of the brush is riveted to the tongue 34 through a laterally elongated slot 44 (see Fig. 3). The pintle 36, to which the tongue is pivoted is riveted through the slot 41 in the cover plate. The slot 44 in the cover plate is elongated horizontally and the slot 41 vertically. The latter slot permits vertical displacement of the tongue and the lower slot permits lateral displacement of the tongue which rotates about the pivot point, i. e. the pintle 36 projecting through the plate 12.

In the embodiment here shown, a spring 50 (see Fig. 1) anchored to the inside face of the cover plate 12 at 51 and 52 crosses over the pintle 36 and urges the tongue 34 downwardly. The inner end of the pintle is provided with the collar 54 which acts as a retainer for the spring 50.

In this embodiment of the invention the brush 32 is free to move laterally with the lateral motion of the wheels 14 and 15 and is free to find its own level by vertical displacement of the tongue 34 which is capable of simultaneous vertical and angular displacement. The downward thrust exerted on the carpet sweeper will determine in part the elevation of the brush.

An elongated handle 60 is affixed to the center of a U-shaped bail 61. The leg 61A of the bail is pivotally mounted to the end 10 by means of a

pintle 63 projecting inwardly from the leg 61A. A corresponding leg (not shown) of the bail is similarly pivotally mounted to the opposite end of the case. The lower end of the bail leg 61A to which the pintle 63 is mounted is provided with an inwardly projecting lip 66 which rides on a stabilizer spring 68. The stabilizer spring 68 is slidably anchored to the end member 10 at 70, and is bent at 68A to provide stationary but removable anchorage at 69.

The lip 66 is shaped so as to exert a substantially uniform downward thrust on the central section of the stabilizer spring throughout the greater portion of the radius of rotation of the bail. When the bail is pivoted to a so-called rest position as indicated by the dotted lines in Fig. 4, the thrust on the stabilizer 68 is substantially released thereby permitting it to spring back to its rest position likewise indicated by dotted lines in Fig. 4. The lip 66, shown in detail in Fig. 9, is shaped in the form of a triple curve. It is apparent that in any position but the direct vertical position, shown in Fig. 4, the lip 66 will contact the spring 68 at only one place on its curvilinear surface, the curve being such that the pressure on the spring 68 is substantially constant except at the extreme points of angular displacement of the bail. At the vertical position however, the lip 66 contacts the spring 68 at the points 66A and 66B serving to resist continued rotation of the bail and handle. This feature acts as a catch whereby the handle will stay in the vertical position shown in Fig. 4 until it is purposely changed. This feature is desirable when the use of the sweeper is temporarily interrupted for some reason. The handle will remain in vertical position until manually rotated therefrom.

The stabilizer spring 68 and its cooperative relationship to the bail 61 is an important feature of the invention and serves to cooperate with the laterally shifting brush to produce more efficient and more wear resistant operation of the sweeper. While the lateral shift of the brush prevents uneven wear of the wheels on the brush pulleys; to a certain extent the stabilization of the downward thrust on the sweeper further increases this wear resistance by equalizing the thrust on the wheels so as to equalize the wear on the wheel axle and also to provide positive drive of the pulley 31 by each of the wheels.

In the foregoing and following embodiments of the invention the sweeper case is illustrated as one of the various types of cases disclosed in my co-pending application Serial No. 7,055, filed February 9, 1948, entitled Carpet Sweeper, and the construction of the case itself being separate and distinct from the mechanisms herein described forms no part of the present invention. Description thereof is therefore omitted.

A simplified form of brush mounting to be used in cheaper models in conjunction with the vertically and laterally shifting wheels is shown in Figs. 5 and 6. In this embodiment the cover plate 12 (Figs. 1 and 2) is replaced by a semi-flexible metal strap 56. A channel cleat 57 mounted on the inside face of the strap provides a laterally elongated socket in which the brush axle 58 is housed. The axle 58 is formed by extending the body 58A through the pulley 30 shown engaged with the ground wheel 14. The rubber bumper 40 extends around the outside of the strap 56 and is sufficiently resilient to permit removal of the brush by flexing the strap outwardly. In this modification of the invention

the brush is free to shift laterally with the wheels; the axle 58 riding in the socket 57. Vertical shifting of the brush relative to the wheels is dependent upon absolute vertical displacement of the wheel hangers determinable by the thrust applied on the sweeper handle.

A modification of the invention is shown in sectional elevation in Fig. 7 and in partial elevation in Fig. 8. This embodiment provides for positive adjustment of the relative elevation of the brush and the wheel by manipulation of the handle, and thus differs from the foregoing embodiments which provided for floating self-seeking adjustment of the brush or wheels. In the sweeper shown in Figs. 7 and 8, a bail 70 is pivotally affixed to end 71 of the sweeper casing 72. The bail 70 is pivotally affixed to the end member 71 by means of a pintle 74 and carries an inwardly extending lip 75, similar to the lip 66 in the foregoing embodiment, which exerts a pressure on a stabilizer spring 76. A brush 78 is mounted on the longitudinal axis of the case as in the foregoing embodiment and is provided with a pulley 79 which is in frictional engagement between a pair of ground wheels of which the wheel 89 may be seen. The wheels and brush pulley are contained in a housing formed between the end 71 and a cover plate 82, and the brush is rotatable on pintle 84 riveted to a tongue 86 and slidable in a groove 88 in the cover plate. The tongue 86 which is free to pivot in a tapered indentation 90 in the cover plate is pivotally mounted at its upper end to the cover plate by the pintle 92 which in this embodiment is rigidly affixed to the cover plate and slidably riveted to the tongue 84. The tongue carries an inwardly projecting pin 94 hereinafter referred to as a cam pin under which a spring 96 (see Fig. 8) projects so as to urge the tongue 86 upwardly.

The bail 70 carries a cam 100 spaced from the bail on the shaft 102. The cam 100 has a curvilinear lower surface 100A which rides on the cam pin 94. The curvilinear surface 100A is eccentric with respect to the axis of rotation of the cam so that the displacement of the cam pin by the cam varies as a function of the angular rotation of the bail 70. With reference to Fig. 8, as the cam 100 is rotated clockwise about its axle 102, the cam pin 94 will be depressed to a greater extent than when the cam 100 is rotated counter-clockwise.

In this embodiment of the invention the relative elevation of the wheels and the rotary brush is positively determined by pivoting the bail towards one side or the other of the sweeper.

The pintle 92, rigidly affixed to the cover plate 82, differs from the pintle 36 in the foregoing embodiment which is rigidly affixed to the tongue and slidably riveted to the cover plate. Vertical displacement of the tongue is accomplished by providing a vertically elongated slot 94 therein through which the pintle 92 is riveted by the cleat 92A which permits the tongue to oscillate. Thus the lateral shifting of the brush simultaneously with the corresponding shift of the wheels is accomplished in the same manner as in the foregoing embodiment but the vertical adjustment of the brush is positively determined rather than being left to vagaries of changing downward force.

As above indicated, the adjustment of the relative elevation of the brush with respect to the wheels may be accomplished through vertical shifting of the wheels rather than the brush. In

any case the shifting of the wheel or the brush takes place with reference to the case itself whereby the relative elevation of the two is changed.

In Fig. 10 I have shown one means of varying the absolute placement of the wheels with respect to the case thus varying the relative positioning of the wheels with respect to the brush. In the embodiment shown in Fig. 10 which is a side elevation of a sweeper casing having an end member 108, the wheels 110, 111 are pivotally mounted at the lower end of vertical hangers 112, 113 respectively. The hangers are in turn pivotally mounted to laterally disposed support arms 114, 115 respectively. The support arms 114, 115 are pivotally mounted to the casing end 108 at 116 and 117 respectively and are pivotally joined together at their innermost ends by a pin 120 journalled through the two.

The bail arm 122 which is provided with a lip 124 engaging a stabilizer spring 125 in the manner heretofore described is also provided with a cam 126 which engages on a roller 128 mounted on the pin 120. The bearing surface 126A of the cam 126 is eccentric with the axis of rotation of the bail leg 122 so that rotation thereof will displace the roller 128 downwardly to a degree depending upon the angular positioning of the bail 122. Since downward displacement of the roller will result in upward displacement of the floor wheels a spring 129 anchored to the end 108 engages the wheel axles so as to urge them downwardly as well as inwardly against the brush pulley (not shown).

In this embodiment of the invention the rotary brush (not shown), may be journalled to the cover plates (not shown) in vertically fixed relationship, inasmuch as the relative elevation of the brush and wheels is determined by vertical displacement of the wheels with respect to the case.

An alternative means of adjustment of the relative elevation of the wheel and brush is shown in Fig. 11 which is an elevation of the inside of a cover plate adapted to be affixed in the manner above described to the end of a sweeper casing. In this embodiment ground wheels 130, 131 are rotatably mounted on the ends of hangers 132, 133 respectively which are rotatably and slidably mounted on pintles 134, 135 respectively projecting inwardly from the cover plate 136. A brush mounting tongue 138 is pivotally mounted at its upper end to the inner face of the cover plate 136 by a pintle (not shown) and extends downwardly through a slot 139 and along the outside face of a frusto-triangular inset 140. The tongue 138 carries a cam pin 142 as in the embodiment shown in Fig. 7 which is urged upwardly by a spring 144 anchored at 145 and 146 to the end plate 128. A cam 148 carried on a bail leg (not shown) by a shaft 149 has a lower curvilinear surface 148A which rides on the cam pin 142 and determines the elevation of the cam pin with respect to the cover plate by the angular placement of the bail leg.

A pintle 152 projecting inwardly from the tongue 138 passes through longitudinally elongated slots 153, 154 formed in the inner end of the hangers 132, 133 respectively. Vertical displacement of the tongue 138 by means of the cam 149 results in a like vertical displacement of the rotary brush (not shown) and a converse vertical displacement of the ground wheels 130, 131 (assuming the pintles 134, 135 are centrally spaced between the hanger ends). Thus for any

given relative displacement between the ground wheels and the rotary brush only half as great a vertical displacement of the tongue 138 is required.

5 Another means of accomplishing the absolute adjustment of the ground wheels and thus the relative adjustment of the wheels, with respect to the brush, is shown in Fig. 12 which is an elevation of the end of a sweeper with the cover plate removed and Fig. 12A which is a section taken on the line 12A—12A of Fig. 12. In this embodiment ground wheels 161, 162 are rotatably mounted on the lower end of hangers 163, 164 respectively which are pivotally mounted to the casing end 160 on pivot pins 166, 167 respectively. A plate 170 having longitudinally elongated slots 171, 172 at opposite ends thereof is mounted to the end on the same pivot pins 166, 167 and is free to slide thereon to the extent of the length of the slots 171, 172.

The plate 170 is provided at opposite ends with a pair of notches 174, 175 and 178, 179 respectively in the upper edge thereof. Each of the hangers 163, 164 carries a transverse pin 163A, 164A respectively hereinafter referred to as the traveling pins. The traveling pins project from both faces of the hangers, one end thereof resting in the notches in the plate 170 and the opposite end thereof riding in cam shaped receptacles 177, 180 in the end 160 of the casing.

30 The opposite pairs of notches in the plate 170 are inversely arranged so that the two traveling pins will rest simultaneously in notches of corresponding depth.

35 Spaced from the center of the plate 170 are a pair of arcuate ears 182, 183. The bail 185, pivotally mounted at 186 to the end of the casing, is provided with an elongated extension 188 which engages one or the other of the ears 182, 183. In the position shown in Fig. 12 rotation of the upper part of the bail 185 about the point 186 in a counterclockwise direction will cause the plate 170 to travel towards the right whereby the inner ends of the traveling pins 163A, 164A will be elevated along the inclined edges 177A, 180A of the respective receptacles until the peak between the deep and shallow notches at each end of the plate passes under the respective pin. The pins will then drop into the corresponding shallow notches 174, 178. In this position the wheels 161, 162 will be elevated with respect to the case an amount equal to the differential in the depths between the deeper and the shallower notches. Thereafter rotation of the bail 185 in the opposite or clockwise direction will operate on the ear 182 to shift the plate 170 in the reverse direction to the position shown in the drawing. In this reverse shift the thrust on the plate will push the traveling pins up the inclined edges 177B, 180B so as to permit the peaks between the two notches in the respective pairs to pass thereunder. Thereafter the pins will fall into the positions shown in Fig. 12.

65 The hangers 162 and 164 which pivot on the pins 166, 167 and ride up and down in accordance with the displacement of the respective traveling pins are provided with the enlarged circular openings 190, 191 respectively to permit vertical and lateral displacement of the hanger with respect to the pivot pin. In this embodiment of the invention a rotary brush (not shown) may be journalled to a tongue pivotally mounted to a cover plate in the manner described above.

It is apparent that the necessary force, as applied by the lateral thrust on the sliding plate 170, to lift the traveling pins up the inclined edges of the cam shaped receptacles in the casing is considerably less than that which would be required to raise the pins along a vertical edge. This force is applied against the pin by the inclined edges of the sliding plate. I have found that the horizontal component thereof is such as to render perpendicular displacement of the pin virtually impossible. This horizontal component is of course a function of the angle of the sides of the notches and can be reduced by decreasing this angle of slope. However, the permissible angle of slope is a function of the obtainable lateral displacement of the plate 170. I have found that the provision of the cam shaped receptacles in the housing which provide inclined edges upon which the pins may travel is the most practical method of obtaining the vertical displacement of the traveling pins, and consequently the hangers, in this type of mechanical movement.

I have described and illustrated an improved carpet sweeper wherein the efficiency and ease of operation have been increased and at the same time the mechanical durability thereof has been extended. This is accomplished by the provision of a laterally shifting brush which in cooperation with means for stabilizing the downward thrust throughout the area of the bottom surface of the casing provides for a constant frictional engagement between the wheels and the floor and between the wheels and the brush pulleys which rotates responsive to the rotation of the wheels. Many modifications in the design of the sweeper and the individual elements thereof may occur to those skilled in the art without departing from the scope of the invention as set forth.

I claim:

1. A carpet sweeper comprising floor wheels arranged in pairs at opposite ends of a casing and rotatable on laterally pivotal and vertically displaceable hangers, a rotary brush mounted in the casing, a pulley on each end of the brush between the wheels of each pair and in driving contact therewith, means for urging the respective wheels of each pair toward the other and into contact with the pulley disposed therebetween, a bail having a separate leg pivotally mounted to each end of the casing and supporting an elongated handle, a separate stabilizer spring connected to each end of the casing at points adjacent the leading and trailing edges thereof, means forming a part of each leg of the bail for exerting a downward thrust on the central portion of each stabilizer spring, a cover plate affixed to each end of the casing and forming a housing with the ends of the casing for the wheels and pulley, a separate tongue pivotally mounted in vertically slidable relationship to the upper part of each of said cover plates and extending downwardly therefrom to a point below the axis of rotation of the brush, the brush being journaled at either end to the corresponding tongue, each cover plate having a tapered inset portion in which the tongue mounted thereto is free to pivot.

2. A carpet sweeper comprising floor wheels arranged in pairs at opposite ends of a casing and rotatable on laterally pivotal and vertically displaceable hangers, a rotary brush mounted in the casing, a pulley on each end of the brush between the wheels of each pair and in driv-

ing contact therewith, means for urging the respective wheels of each pair toward the other and into contact with the pulley disposed therebetween, a bail having a separate leg pivotally mounted to each end of the casing and supporting an elongated handle, a stabilizer spring anchored at the two sides of each end of the casing, means forming a part of each leg of the bail for exerting a downward thrust on the central portion of each stabilizer spring, a cover plate affixed to each end of the casing and forming a housing with the ends of the casing for the wheels and pulley, a tongue pivotally mounted in vertically slidable relationship to the upper part of each of said cover plates and extending downwardly therefrom to a point below the axis of rotation of the brush, the brush being journaled at either end to the corresponding tongue, each cover plate having a tapered inset portion in which the tongue mounted thereto is free to pivot, and means associated with said bail for changing the relative vertical positions of the wheels and brush.

3. A carpet sweeper comprising floor wheels arranged in pairs at opposite ends of a casing and rotatable on laterally pivotal and vertically displaceable wheel hangers, a rotary brush mounted in the casing, a pulley on each end of the brush between the wheels of each pair and in driving contact therewith, means for urging the respective wheels of each pair toward the other and into contact with the pulley disposed therebetween, a bail having a separate leg pivotally mounted to each end of the casing and supporting an elongated handle, a stabilizer spring anchored at the two sides of each end of the casing, means forming a part of each leg of the bail for exerting a downward thrust on the central portion of each stabilizer spring, a cover plate affixed to each end of the casing and forming a housing with the ends of the casing for the wheels and pulley, a tongue pivotally mounted in vertically slidable relationship to the upper edge thereof, each tongue extending downwardly through the cover plate to a point below the axis of rotation of the brush, each cover plate having a frusto-triangular inset portion beneath the point at which the tongue is mounted thereto, the tongue being free to rotate in said inset portion, the rotary brush being journaled at opposite ends of the tongues through a horizontally elongated slot in the corresponding cover plate, and means associated with said bail for changing the relative vertical positions of the wheels and brush.

4. A carpet sweeper comprising floor wheels arranged in pairs at opposite ends of a casing and rotatable on hangers mounted to the casing in laterally pivotal and vertically displaceable relationship, a spring connecting the wheels of each pair so as to urge them together, a rotary brush mounted in the casing, a pulley on each end of the brush between the wheels of each pair and in driving contact therewith, a bail having a separate leg pivotally mounted to each end of the casing and supporting an elongated handle, a stabilizer spring anchored at the two sides of each end of the casing, a lip extending inwardly from each of the legs of the bail adjacent the end thereof, the bottom surface of the lip resting on said spring and having a central concave surface intermediate two convex surfaces, a cover plate affixed to each end of the casing and forming a housing with the ends of the casing for the

wheels and pulley, a tongue pivotally mounted in vertically slidable relationship to the upper part of each of said cover plates and extending downwardly therefrom to a point below the axis of rotation of the brush, the brush being journaled at either end to the corresponding tongue, each cover plate having a tapered inset portion in which the tongue is free to pivot, and means operable by rotation of the bail for changing the relative vertical positions of the wheels and brush. 10

5. A carpet sweeper comprising floor wheels arranged in pairs at opposite ends of a casing and rotatable on hangers mounted to the casing in laterally pivotal and vertically displaceable relationship, a spring connecting the wheels of each pair so as to urge them together, a rotary brush mounted in the casing, a pulley on each end of the brush between the wheels of each pair and in driving contact therewith, a bail having a leg pivotally mounted to each end of the casing and supporting an elongated handle, a stabilizer spring anchored at the two sides of each end of the casing, means forming a part of each leg of the bail for exerting a downward thrust on the central portion of each stabilizer spring, a cover plate affixed to each end of the casing and forming a housing with the ends of the casing for the wheels and pulley, a tongue pivotally mounted in vertically slidable relationship to the upper part of each of said cover plates and extending downwardly therefrom to a point below the axis of rotation of the brush, the brush being journaled at either end to the corresponding tongue, each cover plate having a tapered inset portion in which the tongue mounted thereto is free to pivot, and means operable by rotation of the bail for changing the relative vertical positions of the wheels and brush. 20

6. A carpet sweeper according to claim 5 wherein the means for changing the relative vertical positions of the wheels and brush comprises a pin projecting inwardly from each of said tongues, an eccentric cam mounted to each of the bail arms in engagement with the pin on the corresponding tongue and a suspension spring extending under said pin and urging the same upwardly against the cam. 40

7. Apparatus according to claim 2 wherein each stabilizer spring is anchored at one end to an end of the casing in removable relationship and is held to the casing in slidable relationship at its opposite end. 50

8. A carpet sweeper comprising floor wheels arranged in pairs at opposite ends of a casing and rotatable on laterally pivotal and vertically displaceable hangers, a rotary brush mounted in the casing and having a pulley at each end thereof in frictional contact between the wheels of each pair, means for urging the respective wheels of each pair toward the other and into contact with the pulley disposed therebetween, a bail having a separate leg pivotally mounted at its lower end to each end of the casing, the two legs jointly sup- 55

porting an elongated handle, a separate stabilizer spring lying along and removably and slidably anchored to each end of the casing, means forming a part of each leg of said bail for exerting a downward thrust on the central portion of each stabilizer spring, a cover plate affixed to each end of the casing and forming a housing with the end of the casing for the wheels and pulley, each cover plate having a frusto-triangular indented portion centrally spaced therein, a slot in the upper edge of said indented portion of each housing, a separate tongue pivotally mounted at its upper end to the inner face of each cover plate and projecting through the said slot to lie against and be laterally displaceable along the outer face of the inset portion of the plate, the brush being journaled at opposite ends to the lower end of the separate tongues, each cover plate having a laterally elongated slot through which the brush is journaled to the tongues and which permits the brush to shift laterally with the laterally pivotal tongues, and means for changing the relative vertical positions of the wheels and brush. 20

9. A carpet sweeper comprising floor wheels arranged in pairs at opposite ends of a casing and rotatable on laterally pivotal and vertically displaceable hangers, a rotary brush mounted in the casing, a pulley on each end of the brush between the wheels of each pair and in driving contact therewith, means for urging the respective wheels of each pair toward the other and into contact with the pulley disposed therebetween, a bail having a leg pivotally mounted to each end of the casing and supporting an elongated handle, a cover plate affixed to each end of the casing and forming a housing with the ends of the casing for the wheels and pulley, a tongue pivotally mounted adjacent one of its ends in vertically slidable relationship to the upper part of each of said cover plates and extending downwardly therefrom to a point below the axis of rotation of the brush, the brush being journaled at either end to the corresponding tongue at a point spaced from the point of pivotal mounting of the tongue so that the brush is free to move laterally to be in continuous driving contact with the wheels. 30

EARLE R. SMITH.
